UNITED STATES PATENT OFFICE.

JACOB KAPPLER, OF PHILADELPHIA, PENNSYLVANIA, ASSIGNOR TO GILL & COMPANY, OF PHILADELPHIA, PENNSYLVANIA, A CORPORATION OF PENNSYLVANIA.

DESIGN FOR A LAMP-SHADE.

40,281.

Specification for Design.

Patented Oct. 5, 1909.

Application filed August 9, 1909. Serial No. 512,085. Term of patent 7 years.

To all whom it may concern:

Be it known that I, JACOB KAPPLER, a citizen of the United States, residing at Philadelphia, in the county of Philadelphia and State of Pennsylvania, have invented a new, original, and ornamental Design for Lamp-Shades, of which the following is a specification, reference being had to the accompanying drawing, forming part thereof.

Figure 1 is a side view in elevation of a lamp shade showing my new design. Fig. 2 is a bottom plan view.

I claim:

The ornamental design for a lamp shade, as shown.

JACOB KAPPLER.
